UNITED STATES PATENT OFFICE.

BURNHAM C. STICKNEY, OF ELIZABETH, NEW JERSEY, ASSIGNOR TO UNDERWOOD
TYPEWRITER COMPANY, OF NEW YORK, N. Y., A CORPORATION OF DELAWARE.

TYPE-WRITING MACHINE.

1,124,967.

Specification of Letters Patent. Patented Jan. 12, 1915.

Application filed July 6, 1911. Serial No. 637,049.

To all whom it may concern:

Be it known that I, BURNHAM C. STICKNEY, a citizen of the United States, residing in Elizabeth, in the county of Union and 5 State of New Jersey, have invented certain new and useful Improvements in Type-Writing Machines, of which the following is a specification.

This invention relates to means for releasing the platens from the line-space wheels of typewriting machines.

One object of the invention is to make a secure connection between the line-space wheel and the platen, so that the platen will 10 not either overthrow or underthrow when the usual line-spacing lever is violently actuated, and so as to render the machine more reliable under all other conditions; while permitting easy disconnection of the platen.

Another object is to secure these results by inexpensive, compact and durable mechanism.

Another object is to construct a device which can be readily applied to existing machines.

The accompanying drawings show the preferred form of my invention. In said form, an internal gear is secured to the line-space wheel, and an arm is fixed to the axle to which the platen is also fixed or connected. This arm carries a pinion which meshes with said gear. I also provide a loose arm movable about the platen axle independently of the platen and line space wheel, and having 35 a pinion to mesh with said internal gear. To each of these pinions is fixed a ratchet or toothed wheel, and a spring holds these ratchets in mesh, and they lock together and coöperate with said pinions and gear to prevent relative movement of the platen and line-space wheel. A finger piece is connected to means for separating the ratchets at will, so that the platen may be rotated independently of the line-space wheel; and 40 said spring thereafter returns the ratchet wheels into engagement with each other, thus re-connecting the platen to the line-space wheel. I illustrate also a second loose arm, also carrying a pinion in mesh with said internal gear and provided with a ratchet. Said arm which is fixed to the platen axle occupies a position between the two loose arms, and the same spring operates on the two loose arms to hold their 45 ratchets in mesh with the ratchet device on

the fixed arm. The first pinion (the one on the arm fixed to the platen axle) carries two ratchet wheels, which are oppositely disposed. This is so that the ratchet wheels may engage in such a manner that one positively prevents relative shake or movement of the platen and line space wheel in one direction, while the other positively prevents relative movement thereof in the other direction; so that there can be no lost motion between the platen and line space wheel at any time.

Other objects and advantages will herein-after appear.

In the accompanying drawings, Figure 1 is a side elevation of one end of a platen frame, showing the line space wheel, and illustrating the present improvements in one form. Fig. 2 is an elevation, partly in cross-section, of the line space wheel and connected parts. Fig. 3 is a longitudinal section of the invention. Fig. 4 is a perspective view of the releasing lever. Fig. 5 is an enlarged diagram to illustrate the gear and the interlocking ratchets. Fig. 6 is a sectional end view, showing the releasing lever and casing which incloses the gearing.

The usual cylindrical platen 1 is fixed by a pin 2 upon an axle 3, which is journaled in the usual manner in the ends 4 of a platen frame, and projects beyond said ends and carries at each end a knob 5 fixed to the platen axle. Loose upon the platen axle is a line space wheel 6, having a hub 7. The line space wheel is held in normal position by a detent 8, and is operated by the usual mechanism, including a driving pawl 9. Fixed upon the line space wheel 6 is an annular internal gear 10, seated in an annular flange 11, which projects from the face of the line space wheel. Fixed upon the platen axle 3 is the hub 12 of an arm 13, to the free end of which is pivoted a pinion 14, meshing closely with the gear 10. Loose upon the platen axle 3 is an arm 15, carrying a pinion 16 also in mesh with the gear 10. Also loose upon said axle is an arm 17, carrying a pinion 18 likewise in mesh with said gear. Fixed to the loose-arm pinion 16 is a ratchet wheel 19, and fixed to the pinion 18 is a ratchet wheel 20. These ratchet wheels are similarly formed, but the teeth on one ratchet point oppositely from those on the other ratchet. Fixed to the pinion 14 are two ratchet wheels 21 and 22, set so that 114

their teeth point oppositely, as seen best at Fig. 5; 21 being adapted to mesh with 19, and 22 with 20. A spring 23 holds the ratchets 19 and 20 in mesh with the wheels 5 21 and 22; said spring being connected at one end to an extension 24 of loose arm 15, and at the other end to an extension 25 of loose arm 17; said extensions being preferably below the platen axle 3, or upon the 10 opposite side of said axle from the pinions, for compactness.

To release the platen from the line-space wheel, a button 26 is pressed toward the right at Figs. 1 or 3, said button mounted 15 upon the ends of a pair of stems 27, extending through perforations in the knob 5, and at their inner ends connected to a disk or plate 28, having a hub 29, whereby it is slideable along the platen axle 3. This disk is 20 pressed against and moves a shoulder 30, formed upon a lever 31 of the third order; one end of the lever forked at 32 to bestride the platen axle, and pivoted at 33, Fig. 6, to the arm 13. At its lower end the lever has 25 a finger 34, with a beveled or pointed tip 35, which works between the ends of the extensions 24 and 25, and cams them apart, thereby swinging the arms 15 and 17 away from the arm 13, and releasing all the ratchets. 30 The platen may now be rotated to bring any point thereof to the line of writing, while the line space wheel is held stationary by the detent 8. Upon releasing the finger piece 26, the spring 23 restores the arms 15 and 17, and also returns the finger piece 26 to normal position. The ratchets are again brought into mesh, as at Figs. 2 and 5, and hence the line space wheel is positively secured to the platen. 35 40 It will be seen at Fig. 5 that if it be attempted to rotate the platen and the arm 13 in a direction to carry the pinion 14 bodily to the right, said pinion will tend to rotate upon its own axis, because of its connection with the gear 10; and the teeth of ratchet 22, which are in engagement with the teeth of ratchet 20, tend to turn the latter toward the right, this tendency being however resisted by reason of the engagement of the pinion 18 (fixed to 20) and the stationary gear 10. The ratchet teeth 20, 22 are shaped to rigidly lock in one direction, that is, 20 positively prevents 22 from turning, as afore-said, and hence the arm is prevented from swinging in one direction around the axle 3. At the same time, the ratchet 19, by reason of the engagement of 16 with 10, prevents 21 from turning in the opposite direction; the teeth of 19 being directly set to positively lock 21 from turning in such direction. Hence the arm 13 can budge neither to the right nor to the left while gear 10 remains stationary. This locking effect is secured by making the engaging faces of the ratchet teeth radial, or slightly hooked. 45 50 55 60 65

The inclined faces of the ratchet teeth intermesh of course, but are not relied upon to effect positive interlocking of the members, because of their obliquity.

The ratchets 19, 20, 21 and 22 are preferably made of larger diameter than their pinions, so that the peripheral dimension of each ratchet is greater than that of its pinions, and hence there is less liability of faulty reengagement of the ratchets after 70 their release, while the ratchet teeth may be made finer and more numerous without making the structure unduly weak for its purpose. By making the teeth fine, the liability of catching of the tips or points of one set 75 of ratchet teeth upon those of another at the release of the finger piece 26 is minimized or avoided.

The releasing lever 31 is provided with a dead or dwell surface or edge 36 adjacent 80 to the opposite cams 35; said dwell surface being intended to engage the ends of the extensions of arms 24 and 25 and hold them apart mechanically, so that the operator, by first pressing the button in as far as it will 85 go, may use both hands if desired in adjusting the platen and the work sheet; while upon subsequently pulling out the button, the disk 28 will engage a hook 37 on said lever 31, and pull the same up to normal 90 position, Fig. 3. If the operator does not want to lock the arms apart, he will not press the button in so far.

Other variations may be resorted to within the scope of the invention; and other means 100 may be provided for releasing the platen from the line space wheel. I believe it to be broadly new to use a train of three or more gears or toothed wheels which lock one another against rotation and hence lock the 105 platen to the line space wheel, with provision for separating the members of said train so as to permit independent rotation of the platen. Other novel features will be pointed out in the claims.

Having thus described my invention, I claim:

1. The combination with a platen and a line-space wheel, of a connecting train including a gear secured or connected to said wheel, intermeshing rotary devices also meshing with said gear, one of said rotary devices pivoted upon an arm or member connected to the platen, a spring to hold said intermeshing devices together to connect the platen to the line-space wheel, and a finger-piece having means to separate said rotary devices in any rotative position of the platen to permit the platen to be rotated independently of the line-space wheel.

2. The combination with a platen and a line-space wheel, of a connecting train including a gear secured or connected to said wheel, pinions meshing with said gear, one of said pinions pivoted upon a member con-

nected to the platen, a device connected to each pinion to rotate therewith, a spring to hold said rotary devices in engagement to connect the platen to the line-space wheel, and a finger-piece having means to separate said rotary devices to permit the platen to be rotated independently of the line-space wheel.

3. The combination with a platen and a line-space wheel, of a connecting train including a gear secured or connected to said wheel, a pinion meshing with said gear and pivoted upon a member connected to the platen, a device fixed to said pinion to rotate therewith, a pair of pinions also meshing with said gear, and each having a device to rotate therewith and also to engage the first-mentioned rotary device, for connecting the wheel, and means operated by said tensional 10 means to hold said pair of rotary devices in engagement with the first-mentioned rotary device, means for separating said rotary devices, to permit the platen to be rotated independently of the line-space wheel, and 25 means operated by said tensional means to release said separating means.

4. The combination with a platen and a line-space wheel, of a connecting train including a gear secured or connected to said wheel, a pinion meshing with said gear and pivoted upon an arm or device connected to said platen, a device fixed to said pinion to rotate therewith, a pair of pinions also meshing with said gear, and each having a 35 device to rotate therewith and also to engage the first-mentioned rotary device, for connecting the platen to the line-space wheel, tensional means to hold said pair of rotary devices in engagement with the first-mentioned rotary device, means for separating said rotary devices to permit the platen to be rotated independently of the line-space wheel, and means operated by said tensional 40 means to release said separating means, provision being made for mechanically holding the rotary devices apart, to relieve the operator of the necessity of holding the releasing button in effective position.

5. The combination with a platen, of a line-space wheel for said platen, and a planetary gear lock controllable in any rotative position of the platen, for securing said platen and said line-space wheel against relative rotation.

55 6. The combination with a platen, of a line-space wheel for said platen, a planetary gear lock for securing said platen and said line-space wheel against relative rotation, and means for releasing said planetary gear 60 lock in any rotative position of the platen to permit a relative rotation between said platen and said wheel.

7. The combination with a platen, of a line-space wheel for said platen, a locking 65 gear rolling relatively to said wheel to en-

able a relative movement between said platen and said line-space wheel, and releasable locking means operative in any rotative position of the platen for preventing the rolling of said gear and thereby preventing 70 a relative movement between said platen and said wheel.

8. The combination with a platen, of a line-space wheel for said platen, a gear rolling relatively to said wheel and swinging 75 with the rotation of said platen in a circular orbit concentric with the axis of both said platen and wheel to enable a relative rotation between said platen and said line-space wheel, and releasable locking means movable 80 with said platen for preventing the rolling of said gear and thus preventing a relative rotation between said platen and said line-space wheel.

9. The combination with a platen, of a line-space wheel for said platen, a member moved by a relative movement of said platen and said line-space wheel, locking means to co-act with said member for preventing a relative movement of said platen and said 90 wheel by a movement in one direction, locking means to co-act with said member for preventing a relative movement of said platen and said line-space wheel by a movement in the opposite direction, and releasing 95 means common to both said locking means arranged to concomitantly release both said locking means to enable a relative rotation of said platen and said line-space wheel.

10. The combination with a platen, of a line-space wheel for said platen, a plurality 100 of members rolling relatively to both said parts to enable a relative movement between said parts and arranged to interlock to prevent a relative movement between said parts, and releasing means movable with the platen for disengaging said members to enable the free rolling thereof, and thus to enable a free rotation of the platen relatively to said line-space wheel.

11. The combination with a platen, of a line-space wheel for said platen, a plurality 110 of members rolling relatively to both said parts to enable a relative movement between said parts and arranged to interlock to prevent a relative movement between said parts, and releasing means movable with the platen for disengaging said members to enable the free rolling thereof, and thus to enable a free rotation of the platen relatively to said line-space wheel; said releasing means being 115 arranged to stay set when manipulated to one position or the other.

12. The combination with a platen and a ratchet wheel rotatable relatively thereto, of a train of devices releasably connecting said platen and ratchet wheel, said train comprising a gear, a pinion meshing with said gear and pivoted upon an arm or device, ratchet wheels fixed to said pinion, a pair 125 130

of pinions also meshing with said gear and mounted upon arms which are pivoted to swing about the platen axis independently of each other and of said platen and ratchet 5 wheel, a pair of ratchets, one fixed to each of said pair of pinions to engage the ratchets which are fixed to the first pinion, a spring to bring the ratchets into mesh, and a finger-piece to release the ratchets, to permit rotation of the platen independently of the line-space 10 wheel.

13. The combination with a platen and a ratchet wheel rotatable relatively thereto, of a train of devices releasably connecting said 15 platen and ratchet wheel, said train comprising an internal gear, a pinion meshing with said gear and pivoted upon an arm or device, ratchet wheels fixed to said pinion, a pair of pinions also meshing with said internal gear and mounted upon arms which are revolvable about the platen axis independently of each other and of said platen and ratchet wheel, a pair of ratchets, one fixed to each of said pair of pinions, to engage 20 the ratchets which are fixed to the first pinion, a spring to bring the ratchets into mesh, a cam lever to release the ratchets, to permit rotation of the platen independently of the line-space wheel, and a finger-piece to operate 25 said cam lever, the latter having a dwell portion to hold said pinion-carrying arms mechanically in abnormal positions.

14. The combination with a platen and a line-space wheel, of a train of gears connecting said platen and wheel, and a gear movable into and out of position to lock said train, in any rotative position of said platen.

15. In a typewriting machine, the combination of a platen and line-space wheel, a train of gears connecting said parts, and a locking element movable into and out of position to lock said train, in any rotative position of said platen.

16. The combination of a platen and a line-space wheel having a common axis of rotation, an annular gear secured to said wheel and having internal gear teeth, a cooperating pinion carried by said platen and located between said axis and the annular gear, and a locking element movable into and out of position in any rotative position of the platen, to lock said pinion and annular gear against relative movement.

17. The combination of a platen and a line-space wheel rotatable relatively thereto, a train of gears connecting said platen and wheel, a locking member operable to lock the train of gears against movement in one direction, and a second element to lock said train against movement in the opposite direction.

18. The combination with a platen and a line-space wheel rotatable relatively thereto, of a gear carried by said wheel, intermeshing rotary devices also meshing with said

gear, one of said rotary devices being pivoted upon a member connected to said platen, means to hold said intermeshing devices together to connect the platen to the line-space wheel in any relative position of adjustment of the platen and the line-space wheel, and a finger-piece having means to separate said rotary devices to permit the platen to be rotated independently of the line-space wheel.

19. The combination with a platen and a line-space wheel, of a connecting train including a gear connected to said wheel, pinions meshing with said gear, one of said pinions being pivoted upon a member connected with said platen, a device connected to each pinion to rotate therewith, elastic means to hold said rotary devices in engagement and thereby connect the platen and line-space wheel in any relative position of adjustment, and a finger-piece having means to separate said rotary devices to permit the platen to be rotated independently of the line-space wheel.

20. The combination with a platen and a line-space wheel, of a connecting train including a gear connected to said wheel, a pinion meshing with said gear and pivoted upon a member connected with said platen, a device fixed to said pinion to rotate therewith, a pair of pinions also meshing with said gear and each having a device to rotate therewith and also to engage the first-mentioned rotary device, said devices being operable to connect the platen and line-space wheel in any position in which the line-space wheel may be held, means including a spring to hold said pair of rotary devices in engagement with the first-mentioned rotary devices, and means for separating said rotary devices to permit the platen to be rotated independently of the line-space wheel, said spring also serving to return said separating means.

21. The combination with a platen, of a line-space wheel, a locking gear rolling relatively to said platen to enable a relative movement between the platen and line-space wheel, and releasable locking means to prevent the rolling of said gear and thereby lock the platen to the line-space wheel in any position of adjustment of the latter.

22. The combination with a platen, of a line-space wheel therefor, a connecting train including a gear rolling relatively to said wheel and swinging with the rotation of said platen in a circular orbit concentric with the axis of both said platen and wheel to enable a relative rotation between the platen and line-space wheel, and releasable locking means for preventing said rolling of the gear, said locking means being operable at any point in said swinging movement, thereby preventing rotation between the platen and the line-space wheel.

23. The combination with a platen, of a line-space wheel therefor, a connecting train including members rolling relatively to said platen to permit a relative movement between said platen and wheel and arranged to interlock to prevent a relative movement between said platen and wheel from any relative position to which they may be brought, and releasing means for disengaging said members to enable a free rolling thereof, and thus permit a free relative rotation of the platen and line-space wheel.
24. The combination with a platen, of a line-space wheel therefor, a connecting train including members rolling relatively to said platen to enable a relative movement between said platen and wheel and arranged to interlock to prevent a relative movement between said platen and wheel from any relative position to which they may be brought, and releasing means for disengaging said members to enable the free rolling thereof and thus enable a free relative rotation between the platen and line-space wheel, said releasing means being arranged to stay set when manipulated to one position or the other.
25. The combination with a platen and a line-space wheel, of a train of gears connecting said platen and wheel, and a gear movable into and out of position to lock said train in any relative position of said platen and wheel through means movable with said platen.
26. In a typewriting machine, the combination of a platen and line-space wheel, a train of gears connecting said parts, and a locking element movable into and out of position to lock said train at any position of adjustment of the platen relatively to the line-space wheel, through means movable with said platen.
27. The combination of a platen and a line-space wheel having a common axis of rotation, said wheel being adapted to be held in various positions of angular adjustment, an annular gear secured to said wheel and having internal gear teeth, a coöperating pinion carried by said platen between said axis and the annular gear, and a locking element movable through means movable with the platen into and out of position to lock said pinion and annular gear for any position of adjustment of the line-space wheel.
28. The combination of a platen and a line-space wheel, a train of gears connecting said parts, a locking member operable to lock the train of gears against movement in one direction, and a second locking member to lock the train against movement in the opposite direction, said locking members being operable for any position of adjustment to which the line-space wheel may be brought.
29. In a typewriting machine, the combination with a platen and a line-space wheel, of means to hold the line-space wheel in different positions of adjustment, a train of gears connecting the platen and line-space wheel, and a gear movable through means movable with the platen into and out of position to lock said train for any position of adjustment of the line-space wheel.
30. In a typewriting machine, the combination of a platen, a line-space wheel, a detent engaging said wheel and adapted to hold it in various positions of adjustment, a train of gears connecting the platen and line-space wheel, and a locking element operable independently of the position of the line-space wheel into and out of locking relation to said train, through means movable with the platen.
31. In a typewriting machine, the combination of a platen, a line-space wheel, a connecting train including an annular gear carried by said wheel, a pinion carried by said platen and meshing with the annular gear, a second pinion in mesh with said gear, interlocking devices carried by said pinions, and means for moving said interlocking devices into and out of interlocking engagement.
32. In a typewriting machine, the combination of a platen, a line-space wheel, a connecting train including an annular gear carried by said wheel, a pinion carried by said platen and meshing with the annular gear, a second pinion in mesh with said gear, interlocking devices carried by said pinions, and means for moving said interlocking devices into and out of interlocking engagement independently of the relative position of the platen and line-space wheel.
33. In a typewriting machine, the combination of a platen, a line-space wheel, a connecting train including an annular gear carried by said wheel, a pinion carried by said platen, a second pinion, said pinions meshing with the annular gear, and locking means carried by said pinions and operable to lock the gear and pinions against relative rotation without engagement of said pinions.
34. In a typewriting machine, the combination of a platen, a line-space wheel, a connecting train including an annular gear carried by said wheel, a pinion carried by said platen and meshing with said gear, a second pinion meshing with said gear and movable toward and from said first pinion, and means carried by said pinions to lock the gear and pinions against rotation without bringing the pinions together.
35. The combination with a platen and a line-space wheel, of an intermediate train, locking elements connected to said train and normally in mesh to operatively engage both said platen and wheel for unified movement thereof, and means operable in any position to which said platen may have been rotated for disconnection and reengagement of said

- locking elements, for releasing said locking elements, whereby the platen may be rotated either separately or for line-space movement.
36. The combination with a platen and a line-space wheel, of releasable clutching mechanism connecting them and including a gear, pinions running in mesh with said gear, engaging wheels connected to said pinions, means to hold said engaging wheels in contact with each other, and a finger-piece to separate said engaging wheels.
37. The combination with a platen and a line-space wheel, of releasable clutching mechanism connecting them and including a gear, pinions running in mesh with said gear, engaging wheels connected to said pinions, means to hold said engaging wheels in contact with each other, and a finger-piece to separate said engaging wheels, the diameter of said engaging wheels being greater than the diameter of the pinions.
38. The combination with a platen and a line-space wheel, of releasable clutching mechanism connecting them and including a gear, pinions running in mesh with said gear including an intermediate pinion and a pinion at opposite sides thereof, engaging wheels connected to said pinions and having the same relative arrangement as the pinions, means to hold the side engaging wheels in contact with the intermediate engaging wheel, and a finger-piece to separate said engaging wheels.
39. The combination with a platen and a line-space wheel, of releasable clutching mechanism connecting them and including a gear, pinions running in mesh with said gear including an intermediate pinion and a pinion at opposite sides thereof, engaging wheels connected to said pinions and having the same relative arrangement as the pinions, means to hold the side engaging wheels in contact with the intermediate engaging wheel, and a finger-piece to separate said engaging wheels, the diameter of said engaging wheels being greater than the diameter of the pinions.
40. The combination with a platen and a line-space wheel, of a connecting train comprising a gear concentric with the platen axle and pinions eccentric to said axle, and a clutch composed of engaging wheels respectively carried by said pinions and movable therewith into and out of clutch engagement.
41. The combination with a platen and a line-space wheel, of a connecting train comprising a gear concentric with the platen axle and pinions eccentric to said axle, one of said pinions being movable with the platen, and a clutch composed of engaging wheels respectively carried by said pinions and movable therewith into and out of clutch engagement.
42. The combination with a platen and a line-space wheel, of a connecting train comprising a gear concentric with the platen axle and pinions eccentric to said axle, one of said pinions being movable with the platen, a clutch composed of engaging wheels respectively carried by said pinions and movable therewith into and out of clutch engagement, means to hold said engaging wheels in clutch engagement, and a finger-piece to release said engagement.
43. The combination with a platen and a line-space wheel, of a connecting train comprising a gear concentric with the platen axle and pinions eccentric to said axle, one of said pinions being movable with the platen, a clutch composed of engaging wheels respectively carried by said pinions and movable therewith into and out of clutch engagement, means to hold said engaging wheels in clutch engagement, and a finger-piece to release said engagement.
44. The combination with a platen and a line-space wheel, of a connecting train comprising a gear concentric with the platen axle and pinions eccentric to said axle, and a clutch composed of engaging wheels respectively carried by said pinions and movable therewith into and out of clutch engagement, said engaging wheels having respectively greater peripheral speed than the pinions by which they are carried.
45. The combination with a platen and a line-space wheel, of a connecting train comprising a gear concentric with the platen axle and pinions eccentric to said axle, one of said pinions being movable with the platen, and a clutch composed of engaging wheels respectively carried by said pinions and movable therewith into and out of clutch engagement, said engaging wheels having respectively greater peripheral speed than the pinions by which they are carried.
46. The combination with a platen and a line-space wheel, of a clutch comprising engaging wheels normally in operative connection, said engaging wheels being operatively connected with the line-space wheel, one of said engaging wheels also having a fixed position in relation to the platen for the united movement of said platen and line-space wheel, and means for disconnecting said engaging wheels to render the clutch inoperative and permit relative movement between the platen and line-space wheel.
47. The combination with a platen and a line-space wheel, of a clutch composed of engaging wheels normally in operative engagement, said engaging wheels having gears engaging the line-space wheel, and one of said engaging wheels also having a position in fixed relation to the platen for the united movement of said platen and line-space wheel, the engaging wheels at their point of clutch engagement having greater lineal speed than said gears at their point of engagement with the line-space wheel,

- and means for releasing the clutch engagement, to permit relative movement between the platen and line-space wheel.
48. The combination with a platen and a line-space wheel, of a clutch composed of engaging wheels normally in operative connection, said wheels also having gears in engagement with the line-space wheel, and one of said engaging wheels having a position in fixed relation to the platen for the united movement of said platen and line-space wheel, the point of clutch engagement between said engaging wheels being more distant from the axes of said wheels than are the points of engagement of said gears with the line-space wheel.
49. The combination of a platen, a train comprising a gear, a pinion, an engaging wheel connected to said pinion and of larger diameter than the pinion, an engaging device coöperating with said wheel to oppose the rotation of the pinion, and a line-space wheel connected to said platen by said train.
50. The combination of a platen, a train comprising a gear, a pinion, an engaging wheel connected to said pinion and of larger diameter than the pinion, an engaging device coöperating with said wheel to oppose the rotation of the pinion, a line-space wheel connected to said platen by said train, and a finger-piece connected to means to release said pinion from the control of said engaging device, to permit rotation of the platen independently of the line-space wheel.
51. The combination of a platen, a train comprising a gear, a pinion, an engaging wheel connected to said pinion and of larger diameter than the pinion, a pair or devices engaging said engaging wheel to coöperate therewith to prevent rotation of said pinion, and a line-space wheel, said platen and line-space wheel connected by said train.
52. The combination of a platen, a train comprising a gear, a pinion, an engaging wheel connected to said pinion and of larger diameter than the pinion, a pair of devices engaging said engaging wheel to coöperate therewith to prevent rotation of said pinion, a line-space wheel, said platen and line-space wheel connected by said train, and means to release said pinion from the opposition of said pair of engaging devices.
53. The combination of a platen, a train comprising a gear, a pinion, an engaging wheel connected to said pinion and of larger diameter than the pinion, a pair of devices engaging said engaging wheel to coöperate therewith to prevent rotation of said pinion, and a line-space wheel, said platen and line-space wheel connected by said train, said pair of engaging devices being connected to said gear to be rotated thereby.
54. The combination with a revolute platen and a platen-driving shaft, of a train of mechanism comprising a gear concentric with said shaft, an arm revolute about said shaft, a pinion carried by said arm and meshing with said gear, an engaging wheel on said pinion, means to engage said engaging wheel to oppose the rotation thereof, and a line-space wheel connected to said shaft by said train.
55. The combination with a revolute platen and a platen-driving shaft, of a train of mechanism comprising a gear concentric with said shaft, an arm revolute about said shaft, a pinion carried by said arm and meshing with said gear, an engaging wheel on said pinion, means to engage said engaging wheel to oppose the rotation thereof, a line-space wheel connected to said shaft by said train, and means to release said engaging wheel.
56. The combination with a revolute platen and a platen-driving shaft, of a train of mechanism comprising a gear concentric with said shaft, an arm revolute with said shaft, a pinion carried by said arm and meshing with said gear, an engaging wheel on said pinion, a second arm rotatable about said shaft, a pinion carried by said second arm and in mesh with said gear, an engaging wheel carried by said second pinion, means to press said engaging wheels together to oppose the rotation thereof, and a line-space wheel connected to said shaft by said train.
57. The combination with a revolute platen and a platen-driving shaft, of a train of mechanism comprising a gear concentric with said shaft, an arm revolute with said shaft, a pinion carried by said arm and meshing with said gear, an engaging wheel on said pinion, a second arm rotatable about said shaft, a pinion carried by said second arm and in mesh with said gear, an engaging wheel carried by said second pinion, means to press said engaging wheels together to oppose the rotation thereof, a line-space wheel connected to said shaft by said train, and means for effecting relative movement of said arms to separate said engaging wheels from each other.
58. The combination with a revolute platen and a platen-driving shaft, of a train of mechanism comprising a gear concentric with said shaft, an arm revolute with said shaft, a pinion carried by said arm and meshing with said gear, an engaging wheel on said pinion, a second arm rotatable about said shaft, a pinion carried by said second arm and in mesh with said gear, an engaging wheel carried by said second pinion, a third arm mounted to rotate about said shaft, an engaging wheel on said third arm, means to press all of said

engaging wheels together to oppose the rotation thereof, and a line-space wheel connected by said train to said platen.

59. The combination with a revoluble platen and a platen-driving shaft, of a train of mechanism comprising a gear concentric with said shaft, an arm revoluble with said shaft, a pinion carried by said arm and meshing with said gear, an engaging wheel on said pinion, a second arm rotatable about said shaft, a pinion carried by said second arm and in mesh with said gear, an engaging wheel carried by said second pinion, a third arm mounted to rotate about said shaft, an engaging wheel on said third arm, means to press all of said engaging wheels together, a line-space wheel connected by said train to said platen, and means to separate the engaging wheels to permit the rotation of the platen and line-space wheel.

60. The combination with a revoluble platen and a platen-driving shaft, of a train of mechanism comprising a gear concentric with said shaft, an arm revoluble with said shaft, a pinion carried by said arm and meshing with said gear, an engaging wheel on said pinion, a second arm rotatable about said shaft, a pinion carried by said second arm and in mesh with said gear, an engaging wheel carried by said second pinion, means to press said engaging wheels together, and a line-space wheel connected to said shaft by said train, each of said engaging wheels being of greater diameter than its pinion.

61. The combination with a revoluble platen and a platen-driving shaft, of a train of mechanism comprising a gear concentric with said shaft, an arm revoluble with said shaft, a pinion carried by said arm and meshing with said gear, an engaging wheel on said pinion, a second arm rotatable about said shaft, a pinion carried by said second arm and in mesh with said gear, an engaging wheel carried by said second pinion, means to press said engaging wheels together, a line-space wheel connected to said shaft by said train, each of said engaging wheels being of greater diameter than its pinion, and means for effecting relative movement of said arms to separate said engaging wheels from each other.

62. The combination with a revoluble platen and a platen-driving shaft, of a train of mechanism comprising a gear concentric with said shaft, an arm revoluble with said shaft, a pinion carried by said arm and meshing with said gear, an engaging wheel on said pinion, a second arm rotatable about said shaft, a pinion carried by said second arm and in mesh with said gear, an engaging wheel carried by said second pinion, a third arm mounted to rotate about said shaft, an engaging wheel on said third arm,

means to press all of said engaging wheels together, and a line-space wheel connected by said train to said platen, each of said engaging wheels being of greater diameter than its pinion.

63. The combination with a revoluble platen and a line-space wheel, of a train connecting them and comprising a gear, a pinion meshing therewith, a companion pinion meshing with said gear, interengaging means connected to said pinions for enabling each to oppose the rotation of the other, and means operable manually to disengage said interengaging means and thereby disconnect the line-space wheel and platen while the latter is in any rotative position.

64. The combination with a revoluble platen and a line-space wheel, of a train connecting them and comprising a gear, a pinion meshing with said gear, interengaging means connected to said pinions for enabling each to oppose the rotation of the other, and a finger-piece operable to manually effect release between said pinions while the platen is in any position of rotation.

65. The combination with a platen and a line-space wheel, of normally operative locking means comprising a train of planetary gears carried in part by said platen and in part by said line-space wheel, and means to lock said train; and means carried by the platen for rendering said locking means inoperative in any rotative position of the platen.

66. The combination with a platen and a line-space wheel, of an intermediate locking train comprising elements connected to the platen and line-space wheel for relative rotation when the platen and line-space wheel are relatively rotated, said elements normally in operative meshed engagement preventing relative rotative movement of said wheel and platen, and means movable with said platen operative in any line-space position of said platen to release said train from its operative engagement and permit individual movement of said platen.

67. The combination of a train comprising a gear, a pinion meshing with said gear, interengaging means for opposing the rotation of said pinion, said pinion and said interengaging means mounted to revolve bodily with said pinion, manually operable means to disengage said interengaging means, and a platen and line-space wheel connected by said train, said disengaging means operable to disconnect the line-space wheel and platen while the platen, line-space wheel, pinion and interengaging means are in any rotative position.

68. The combination of a train comprising a gear, a pinion meshing with said gear, interengaging means for opposing the rota-

tion of said pinion, said pinion and said interengaging means mounted to revolve bodily with said pinion, manually operable means to disengage said interengaging means, a platen and line-space wheel connected by said train, and means for releasing said pinion from the control of said interengaging means independently of the

rotative position of the platen, the line-space wheel, the pinion and the interengaging means.
